UNITED STATES PATENT OFFICE.

RICHARD L. BINDER, OF PHILADELPHIA, PENNSYLVANIA.

BALING DEVICE.

1,254,878.

Specification of Letters Patent. Patented Jan. 29, 1918.

Application filed December 26, 1916. Serial No. 138,768.

To all whom it may concern:

Be it known that I, RICHARD L. BINDER, a citizen of the United States, residing in the city of Philadelphia, county of Philadelphia, and State of Pennsylvania, have invented certain Improvements in Baling Devices, of which the following is a specification.

My invention is an improved device to 10 provide a simple, inexpensive and efficient baler for waste products, such as paper, rags and the like, particularly for domestic use, but it is adapted for baling purposes generally.

15 A characteristic feature of my improved device is the combination of a bin or case having the form of a truncated pyramid, to serve as a container or retainer for the material to be baled, with means for pressing the 20 material in the bin, tying the pressed material, and delivering the finished or tied bale.

Further features of advantage reside in the peculiar details of construction involved in the combination, as will more fully appear 25 from the following description and the accompanying drawings in illustration thereof.

In the drawings, Figure 1 is a part sectional side elevation of a bin or receptacle comprised in my invention; Fig. 2 is a vertical sectional view taken transversely through a baling press embodying my improvements; Fig. 3 is an elevation of a ram or compressing device and its lever connected to form a rammer adapted to be operated manually; and Fig. 4 is a view of the ramming mechanism at right angles to the position shown in Fig. 3, with the top of the lever or handle broken away.

As shown in the drawings, my invention 40 comprises a bin or receptacle provided with a rectangular bottom frame 1 composed of angle iron having inwardly and downwardly extending flanges, a bottom 2 supported upon and fixed to the inwardly extended flanges 45 of the angle irons, and transversely extending boards or strips 3 fixed to the bottom 2 and separated by the spaces forming transverse tie wire ways 4.

A back 5 is fixed at its bottom to the angles 1 and at its sides to the ends 6 by the angles 7. The ends 6 are attached for approximately half the length of their bottom edges, measured from the back 5, to the angles 1 and at their one side to the back 55 by the angles 7, the freedom of the forward part of the ends 6 permitting them to spring

outwardly to facilitate the removal of the bale. The back is provided at its top with the outwardly turned flange 8 and in its body with the upwardly extending slots 9 60 registering with the respective ways 4. The ends 6 are provided with the outwardly turned flanges 10 at their tops at the elevation of the flange 8. A detachable front 11 is connected at its bottom with the front 65 angle 1 by means of clips 12 fixed to the angle and into which the lower part is adapted to be entered, the ends of the part 11 having angles 13 fixed thereto so that a leg thereof will engage the outsides of the adjacent parts of the ends 6. Angles 14 are fixed to the inner surface of the part 11, near its ends, to engage the inner surfaces of the ends 6, coöperating with the angles 13 in connecting the parts 6 and 11 firmly. An outwardly 70 turned flange 15 is formed on the top of the part 11 at the level of the flanges 10 and slots 16 are formed in this front member in the plane of the respective slots 4 and 9. Handles 17 have journals 18 which turn in bearings 19 fixed to the ends 6 and an angle 20 on a journal 18 is adapted for locking the front 11 in place when the handles 17 are raised, the front being prevented from moving upwardly in its position in engagement 80 with the ends 6 by the engagement of the end flanges 10 with the registering leg of the angles 13.

It will be observed that the back, front and ends taper from the bottom upwardly so that 90 the receptacle formed thereby is a truncated pyramid standing on its base. This construction has the function of holding down the material compressed therein.

A ram 21 coöperates with the lever or 95 handle 22 and the bin described for pressing the material, such as waste paper, which is to be baled.

The ram contains a longitudinal slot 23 and registering top and bottom holes 24 and 100 24' for the passage of the lever or handle 22 and its connecting parts necessary to the operation of the ram. Open bearings 25 are formed in the ram on opposite sides of the slot 23. The handle 22 is provided at 105 an end thereof with a hook 26 for engaging the flange 8 on the back of the bin, with the laterally extending studs 27 for engaging the bearings 25, and with the adjustable yoke 28. This yoke is provided with 110 the hooks 29 for engaging the flange 15 when the part 22 is used as a lever in the

relation shown in Fig. 2, and with the pin 30 and chain 31 for engaging the part 22 in the ram 21 in the relation shown in Fig. 3.

It will be understood that when the end 5 of the handle 22 is inserted longitudinally in the ram 21, it is held in the desired position by passing the pin 30 through the hole 21' at the top of the slot 23 and through a hole 32 in the handle, and looping the chain 31 10 over the pin 21" on the ram, the hooks 29 being disposed between the bearings 25.

It will be understood that the bin is adapted to be used as a receptacle for holding waste paper as it accumulates and when 15 filled with loose paper can be readily consolidated to substantially reduce its bulk by manually ramming it, using the device for ramming that is shown in Fig. 3. When it is necessary as a result of the accumulation 20 to press the material, the handle 22 is passed transversely through the ram, the hook 26 is engaged with the flange 8, and the studs 27 are engaged in the bearings 25, the handle being operated as a lever to force the ram 25 down upon the material, where it is held under pressure by the yoke 28 through the engagement of one of its hooks 29 with the flange 15.

When the receptacle has been filled to the 30 desired extent with the consolidated paper, bale wire 33 is slipped through the grooves 4, by way of the bottoms of the slots 9 and 16, and is drawn over the consolidated mass through the respective slots, the wire being 35 drawn up and secured to form ties for the bale in the usual manner.

The handle and ram having been detached from the bin, the handles 17 are turned down to withdraw the parts 20 from engagement with the front 11, whereupon the latter is drawn out at its top, so that the legs of its angles 13 registering with the ends 6 clear the flanges 10, and are lifted from engagement with the clips 12. When the front 45 11 is thus removed, the ends 6, on account of being attached to the angles 1 for only half their lengths, spring outwardly, and an opening is provided through which the bale may be removed.

Having described my invention, I claim: 50
1. A baler comprising a bin having an angle iron frame, a rectangular bottom supported thereon, cross pieces supported by said bottom in separated relation to provide ways, upwardly tapered ends having portions of their bottoms fixed to said frame, an upwardly tapered back having its bot-

tom fixed to said frame and its ends fixed to the ends aforesaid, and an upwardly tapered front having its bottom connected 60 in movable relation with said frame and its ends connected with said ends first named, said back and front having slots therein registering with said ways.

2. A baler comprising a bin having the 65 form of a truncated pyramid with outwardly turned flanges at the tops of oppositely disposed parts thereof, in combination with means engaged by said flanges for pressing material contained in said bin. 70

3. A baler comprising a bin having a base, a movable side connected to said base and provided with end flanges, in combination with ends adapted to be engaged by said flanges, said ends having means coacting 75 with flanges aforesaid for holding said side in assembled relation thereto.

4. A baler comprising a bin having the form of a truncated pyramid with ends provided with outwardly extending flanges and 80 a detachable side provided with end flanges adapted for engaging the ends aforesaid and the flanges thereon.

5. A baler comprising a bin in combination with a ram and a lever having means 85 for engaging it in fulcrumed relation to a side of said bin, means for engaging it in bearing relation with said ram, and a yoke for engaging it to a side of said bin whereby said ram is adapted to be maintained under 90 pressure.

6. A baler comprising a bin in combination with a ram containing a slot, and a handle adapted to pass through said slot, said handle having a hook for engaging said 95 bin, means for engaging said ram so as to move the same, and an adjustable yoke provided with a hook for engaging said bin to hold said ram under pressure.

7. A baler comprising a bin having a removable side, in combination with juxtaposed expandible sides for facilitating the removal of contents thereof.

8. A baler comprising a bin having a bottom and expandible sides in combination 105 with a side having movable connections with said bottom and said expandible sides, said side having flanges for engaging said expandible sides and holding them against expansion.

In testimony whereof I have hereunto set my name this 20th day of December, 1916.

RICHARD L. BINDER.
